POT CLEANER

Frederick A. Pusch, Brooklyn, N. Y.

Application November 29, 1951, Serial No. 258,803

4 Claims. (Cl. 51—185)

1

This invention relates to the manufacture of a cleaning cloth that is especially adapted for the polishing and cleaning of metal, plastic and enamel pots, pans and dishes as well as vitreous ware as bath tubs, wash basins, oven glassware and china.

The invention is fully disclosed in the following detailed description and drawings forming a part thereof in which

Figure 1 is a plan view of a cleaning or pot cloth embodying a form of the invention;

Fig. 2 is a cross-section taken on the lines 2—2 of Fig. 1;

Fig. 3 is a cross-section taken on the line 3—3 of Fig. 1;

Fig. 4 is a plan view of a modified form of the invention and Figs. 5 and 6 are cross-sections taken on the lines 5—5 and 6—6, respectively, of Fig. 4;

Fig. 7 is a plan view of a still further modification of the invention.

Referring to the drawings and the construction shown therein, the numeral 1 designates my improved cleaning cloth, the same comprising a deep pile fabric 2, preferably composed of the so-called terry cloth or Turkish towelling and having uncut pile loops 3 forming the nap thereof. Such loops are each coated with a layer 3' of plastic composition and are filled with beads 3" of the same composition, the same being desirably sprayed thereon as the compressed air in the spray will tend to maintain the loops of the cloth upright and thus facilitate both the coating of the loop threads and the internal filling of the loops 3 themselves.

Following the spraying of the plastic composition on to the loops aforesaid, the treated cloth is baked in an oven at a sufficiently high temperature and for a sufficient time to thoroughly evaporate the water or other liquid vehicle of the spray composition and to set the solid contents thereof into an elastic, water-insoluble state or condition on the treated fibers of the loops. Thereupon, the baked cloth is removed from the oven. The recovered cloth is then extended to its full length and marginal bands such as a, b, c, d, g, or h are pasted along both sides of all of its edges, preferably by a controlled dipping operation, and then if it be desired to form cleaning cloths of the forms illustrated in Figs. 1 or 7, such as the cloths 1 or 1', the pasted cloth is folded on itself either along the fold line F (see Fig. 1) or else along the fold line F' (see Fig. 7), in order to form a flap member 4 of rectangular configuration or a flap mem-

2

ber 11 of triangular configuration that is about one-quarter the size of the main body 10 of the cloth shown in Fig. 7. After being so folded, the cloth is again baked while supplying sufficient pressure to the flap to firmly adhesively unite the same to the underlying cloth.

In the form of the invention illustrated in Fig. 4 a separate pad member 15, formed of the same kind of treated terry cloth as that in the forms of the invention shown in Figs. 1 and 7, is pasted with waterproof cement along both sides of all of its edges. Thereupon, the pad element is folded about the central fold line F'' and caused to envelop the upper end of the cloth 16, which latter is composed of terry cloth treated as aforesaid, after which the cloth 16 with the pad 15 applied thereto is again baked in the oven while applying sufficient pressure to the pad to adhesively unite both of the sides of the same to the enveloped cloth 16.

For the plastic spraying composition I preferably employ a water solution of a urea-formaldehyde resin with which I incorporate a suitable plasticizer in the well known manner together with from about 10% to about 25% of a finely divided abrasive filler, as for example marble dust, powdered pumice, silica dust or emery dust, as such plastic being water-soluble any fire hazard during the drying of the spray coating applied to the fabric is eliminated. Other plastics which are somewhat elastic, such as Lucite and cellulose acetate, for example, may also be used in lieu of the aforesaid plastics.

I am well aware of the Patent No. 2,375,585 wherein is disclosed a plastic abrasive pad formed of water-repellent plastic. The plastic in the form of a web is folded on itself and the opposed marginal cut ends are sealed together. These pads being "unaffected by water" (page 2, lines 19 and 20, col. 1) are incapable of drinking up water, as do the warp and woof of applicant's pot cloth, and being thereby rendered soft and pliable. Accordingly, applicant disclaims as being without the scope of the appended claims any such patented construction.

Applicant's pot cloth is designed for heavy duty cleaning of pots, pans and sanitary ware and the relatively thick flap or pad formed by folding the body of the base cloth on itself or else by cementing a separate folded member of cloth similar to the base cloth serves to protect the fingers and admits of the application of higher pressure through the pad thereby materially aiding in the removal, by attrition, of food incrustations, burnt-on food and the like clinging

to pots and pans or sanitary ware. Moreover, the single edge *f* (see Fig. 1), the double reinforced edges *g* and *g'* and the oblique reinforced edges *h* and *h'* function as extremely effective non-metallic, non-ravelling scraper members and, in the case of the scrapers *h*, *h'*, the scraping action occurs on both the forward as well as the return strokes due to their aforesaid oblique disposition.

As is apparent from an inspection thereof, the coated loop fibers and the encased beads 3' constitute knuckles, so-to-speak which of themselves serve as effective debris-removal elements during a cleaning operation with my improved pot cloth.

Since, in the construction of pot cloth shown in Fig. 4 and Fig. 5 there are two opposed scraper members, it is unnecessary to first observe which side of the cloth is up before commencing the use of the same.

The lateral re-inforced edges 17, 17' (see Fig. 1) and 18, 18', 18'' (see Fig. 6) because of their short span constitute extremely effective scraper members.

The limitation of the cemented areas to the bands extending marginally of the cloth insures that the terry cloth component base fibers will remain soft, pliable and highly absorptive of water, more especially soapy water and detergent solutions. So also do the pads formed of such cloth remain soft and flexible.

My improved cleaning cloth is designed for heavy duty work in the cleaning of pots, pans and the like since the folded flap member or members materially aids in the dislodging of food encrusted or otherwise obstinately adhering to the surfaces being cleaned, particularly since the leading flap edges which are re-inforced and strengthened by the additional adhesive required to unite it effectively to the underlying cloth constitute a relatively rigid ridge which functions as a scraper.

Among the outstanding advantages of the aforesaid cloth construction are the complete absence of any metal therein, the ability of the uncoated warp and woof of the fabric to drink up water and the effectiveness of the plastic beads encased in the loops 3 for the removal of obstinate incrustations and the like from metal or enamel surfaces. The flap member has still another function, namely it forms a thicker pad in the area covered thereby and thus admits of the user applying considerably greater pressure through the fingers upon the incrustation or the like which it is desired to remove from a utensil.

One of the advantages of the pad disclosed in Fig. 7 wherein the flap is of triangular configuration resides in the fact that the flap admits of a to-and-fro scraping action being possible to perform and one of the advantages of the pad shown in Fig. 4 is that the provision of a scraper on both sides of the cloth eliminates the necessity for the user observing on which side of the cloth the scraper is located as the action is the same regardless of which side is up.

As must be apparent from the foregoing de-

scription, the mere manipulation of a folded cloth held in the hand of a user would be wholly ineffectual for dislodging the incrustations and the like from surfaces of pots, pans and sanitary ware because, unless the fold was cemented to the underlying cloth it would not retain its shape and furthermore as the cloth would not have any re-inforced edges it would be altogether too pliable to be useful.

Having thus described the invention, what I claim and desire to secure by Letters Patent of the United States is:

1. As a new article of manufacture, a cleaning cloth composed of a looped fabric of the nature of terry cloth the major portion of the warp and woof whereof is highly pliable and water-absorptive and the nap on at least one side thereof being in the form of separate loops which are coated and filled with a soap-resistant, water-insoluble plastic, said cloth being folded on itself to form a flap element of an area considerably less than one-half that of the underlying cloth and the edges of the flap element being adhesively united to the underlying cloth and being re-inforced with cementitious material to form scraper means.

2. As a new article of manufacture, a cleaning cloth composed of a looped fabric of the nature of terry cloth the major portion of the warp and woof whereof is highly pliable and water-absorptive and the nap on at least one side thereof being in the form of separate loops which are filled and coated with a water-insoluble, soap-resistant resinous plastic and said cloth being folded on itself to form a flap element and said flap element being adhesively united along its free edges to the portion of the cloth lying beneath the same and at least one of said free edges being re-inforced with stiffening cementitious material to constitute the same a scraper.

3. A new article of manufacture as claimed in claim 2 wherein the flap element is of triangular configuration.

4. A new article of manufacture as claimed in claim 2 wherein the nap on both sides of the terry cloth is in the form of uncut loops which are filled with a water-insoluble, soap-resistant plastic.

FREDERICK A. PUSCH.
